UNITED STATES PATENT OFFICE

146,525

DESIGN FOR A BOTTLE

Emile Scheemaeker, Blackstone, Mass.

Application September 12, 1945, Serial No. 122,054

Term of patent 14 years

(CL. D58—6)

To all whom it may concern:

Be it known that I, Emile Scheemaeker, a subject of the Kingdom of Belgium and a resident of Blackstone, in the county of Worcester and State of Massachusetts, have invented a new, original, and ornamental Design for a Bottle, of which the following is a specification, reference being had to the accompanying drawing, forming part thereof.

Figure 1 is a side elevation of a bottle, showing my new design.

Figure 2 is a sectional view of the same taken on line 2—2 of Figure 1, looking in the direction of the arrows.

Figure 3 is a sectional view of the same taken on line 3—3 of Figure 1 looking in the direction of the arrows.

I claim:

The ornamental design for a bottle, as shown.
EMILE SCHEEMAEKER.
